UNITED STATES PATENT OFFICE.

PHILIPP STAPP, OF MUNICH, GERMANY.

APPARATUS FOR STEAMING AND DRYING TEXTILE FABRICS.

1,115,982.

Specification of Letters Patent.

Patented Nov. 3, 1914.

Application filed April 16, 1914. Serial No. 832,326.

To all whom it may concern:

Be it known that I, PHILIPP STAPP, a citizen of the German Empire, and residing at Munich, Germany, have invented certain new and useful Improvements in Apparatus for Steaming and Drying Textile Fabrics, of which the following is a specification.

My invention relates to apparatus for finishing freely guided, pressed and shrunk fabrics by steaming and drying them, and a primary object is to provide improved steaming and drying apparatus for effectively finishing fabrics in which the steam generator of a steaming and drying table known in itself is connected with a steamer over which the web of fabric runs, whereupon the web is contacted by a current of hot air which flows against it through a sieve from the interior of the container surrounding the steam generator. In order to enable the air to be uniformly mixed with and heated by the hot gases I partially surround the steam generator with a jacket which leads upward the hot gases which flow together with the air in the container through the wire sieve at the outlet of the container.

The invention consists in the construction, arrangement and combination of parts described hereinafter and pointed out in the claims.

An illustrative embodiment of the invention is represented by way of example in the accompanying drawings, wherein:

Figures 1 and 2 are side elevation, and end elevation or partly in section, respectively, showing a preferred embodiment of my invention.

Referring to the drawing I have there shown a steaming and drying table or bench comprising a known arched flat-topped metal box or container 1, 2, 3, 4, whose two end walls 3 and 4 are provided with inlets 5 for the outside air, and which contains a cylindrical steam generator 6 heated by the heating apparatus 10. The steam generator may be heated by liquid fuel, gas or electrical sources of heat. The steam generator 6 is covered at one or both ends by panes of glass 8, 9 carried by circular mounts 7 which at the same time connect the generator with the end walls 3, 4 of the metal container.

The cylindrical steam generator 6 is surrounded at both sides by the jacketing plates 12, 12 which are turned inward at the top and deflect the hot gases rising from the pipe 10. Between these plates is a gap 13'

through which the hot gases pass upward together with the heated air which enters through the inlets 5, and then pass out of the container through the finely perforated plate or sieve 13. The strainer which mixes the hot gases and air has arranged above it a steamer comprising a trough and an endless belt guided over two guide rolls, and the current of hot air is guided directly against the curved bottom of the trough and the lower side of the belt. The steamer proper is arranged above this wire sieve 13 which covers the outlet of the container and can be closed by a perforated plate or similar means. This steamer comprises the open trough 18 having the curved bottom 18' and an endless belt 19, 19' which is guided over the guide rolls 20, 23 mounted laterally on the trough 18. One of these rolls is provided with a crank-handle 24 or a mechanical driving device. The fabric 27 is led over the belt 19 of the steaming and drying table in the direction of the arrow shown. The steam generated in the generator 6 passes through the pipes 15 into the trough 18 where it passes through the textile belt 19 and enters into the fabric which is to be steamed and subsequently dried.

The current of hot air which flows out of the container 1, 2, 3 through the sieve 13 has a multiple action in that it flows against the lower side 19' of the belt 19 and evaporates the moisture contained in the same. Part of the heat of this current of hot air directed against the belt is imparted, however, to the bottom 18' of the trough 18, so that any water of condensation which collects is at once evaporated by this indirect heating and the fabric is steamed with steam which is as dry as possible. That part of the current of hot air whose heat is imparted neither to the belt 19, 19' nor to the trough 18, but is deflected toward both sides of the trough and against the fabric 27 serves, on the one hand, for pre-heating the fabric 27 before it passes over the steamer and, on the other hand for drying it after the steaming, so that the web of fabric leaving the steamer is effectively dried.

I claim:

1. In apparatus for steaming and drying textile fabrics, the combination with a container having an outlet in the top thereof and air inlets, a steam generator in the container, means for heating the generator, and a sieve mounted in said outlet, of a steamer

comprising a hollow body and a covering around the same, and pipes connecting the generator with the steamer, the steamer being so disposed relatively to the said outlet that a web of fabric passed over the steamer and the outlet is steamed and is contacted by the current of hot air issuing through said sieve.

2. In apparatus for steaming and drying textile fabrics, the combination with a container having an outlet in the top thereof and air inlets, a steam generator in the container, means for heating the generator, a jacket partially surrounding the generator for leading a gaseous heating medium from said means past the generator and to said outlet, and a sieve mounted in said outlet, of a steamer comprising a hollow body and a covering around the same, and pipes connecting the generator with the steamer, the steamer being so disposed relatively to the said outlet that a web of fabric passed over

the steamer and the outlet is steamed and is contacted by the current of hot air issuing through said sieve.

3. In apparatus for steaming and drying textile fabrics, the combination with a container having an outlet in the top thereof and air inlets, a steam generator in the container, means for heating the generator, and a sieve mounted in said outlet, of a steamer comprising a trough located vertically above said outlet, a guide roll at each side of the trough, and an endless belt carried by the guide rolls and surrounding the trough; and pipes connecting the generator with the steamer.

In testimony whereof, I affix my signature in the presence of two witnesses.

PHILIPP STAPP.
